UNITED STATES PATENT OFFICE.

JOHN Q. FINCH, OF SAN FRANCISCO, CALIFORNIA.

LUBRICATOR.

SPECIFICATION forming part of Letters Patent No. 518,058, dated April 10, 1894.

Application filed March 5, 1891. Serial No. 383,888. (No model.)

To all whom it may concern:

Be it known that I, JOHN Q. FINCH, a citizen of the United States, residing in the city and county of San Francisco, State of California, have invented an Improvement in Automatic Oil-Cups; and I hereby declare the following to be a full, clear, and exact description of the same.

My invention relates to certain improvements in lubricating devices for machinery; and it consists of the construction and combination of devices which I shall hereinafter fully describe and claim.

Referring to the accompanying drawings for a more complete explanation of my invention, Figure 1 is a vertical sectional view of the cup showing its application to a journal. Fig. 2 is a view of the cone and its cap.

A is the cup which, in the present case, I have shown made cylindrical in form, and B is a central cone extending from the bottom up to a point just below the top of the cup. This cone has a hole made through it, preferably conical in shape, as herein shown, having the smallest diameter at the top and the largest at the bottom.

C is a rod or wire extending upward through the opening in this central cone, and at the upper end it is bent sharply over the side of the cone so that it dips into the cup outside of the cone, as shown at C'. The opposite end of this rod or wire extends down through an opening in the journal-box or bearing until its end is in contact with the revolving shaft or pin which is to be lubricated by it, or if it be used to lubricate sliding surfaces, it will rest upon one of these surfaces.

The rod or wire C is preferably made by twisting up small wires of metal into a small wire rope or strand of sufficient size to pass up through the opening in the cone, and to move freely but without too much play within it. By the use of a twisted wire the oil is carried along the grooves between the wires by capillary action. But capillary action alone would not be sufficient to cause the flow of oil necessary to lubricate a bearing by means of a twisted wire. The flow of oil along the wire is aided by vibration due to the rubbing motion of the shaft along the point of the wire. It is also aided by the continual tearing away of the drop of oil which forms around the base

of the wire where it rests upon the shaft. As the twisted wire constitutes really a metallic wick it conducts heat from the shaft to the oil with which it is in contact causing it to become more fluid and to flow more readily along the wire. Since the vibration, the tearing away of the oil, and the heat all cease when the shaft stops revolving, it is evident that feeding of oil must stop or be reduced to an inappreciable amount. The heat of a journal increases with the load upon it. The rate of lubrication must, therefore, increase on account of the conductivity of the metallic wick.

The cup A may be made of metal, or of other suitable or desirable material, but I prefer to make it of glass, hard rubber, or other insulating material, and is set into an exterior metal case or socket D which is fitted to be screwed into or secured over the opening in the journal-box through which the lubricant passes to the journal. A small cap E is fitted over the top of the cone, this cap having a slot in one side to allow the bent arm or wire to pass through it and dip into the lubricant within the cup. A cap F is also placed over the top of the cup A to prevent dust from getting into the oil, and also to prevent the oil from being thrown out when the cup is set upon a crank pin, or any other place where the cup itself is subjected to violent motion. Both the caps E and F, in this case, serve to prevent the oil from being thrown out of the cup either into the cone, or over the outside edges by reason of the motion.

I have experimented considerably upon these cups, and I find that when made of iron or other metal, the oil will be drawn out from the cup with very much greater rapidity than when it is made of glass, and that by making the cup of glass with the metallic wire constructed as above described, the feed from the cup will always be slow and constant, and only while the machinery is in motion.

Having thus described my invention, what I claim as new, and desire to secure by Letters Patent, is—

As a new article of manufacture, a lubricating cup having a centrally perforated stem projecting from its lower end, having means for removably connecting it centrally above the journal to be lubricated, said cup being composed of an exterior metal case with an

interior lining forming a receptacle, a cone concentric with the interior walls of the receptacle having a vertical central passage continuous with the passage in the exterior 5 stem, and a metallic conductor impervious to oil, bent upon itself with one end resting within the receptacle and the other extending down through the cone and stem, so as to

rest in operative contact with the surface to be lubricated, when the cup is in place.

In witness whereof I have hereunto set my hand.

JOHN Q. FINCH.
